(57) **CLAIM**

The ornamental design for a front door lining, as shown and described.

DESCRIPTION

FIG. 1 is a front left perspective view of a front door lining showing our new design;

FIG. 2 is a rear left perspective view of the design shown in FIG. 1;

FIG. 3 is a rear right perspective view of the design shown in FIG. 1;

FIG. 4 is a front right perspective view of the design shown in FIG. 1;

FIG. 5 is a left view of the design shown in FIG. 1;

FIG. 6 is a right view of the design shown in FIG. 1;

FIG. 7 is a rear side view of the design shown in FIG. 1;

FIG. 8 is a front side view of the design shown in FIG. 1;

FIG. 9 is a top view of the design shown in FIG. 1; and,

FIG. 10 is a bottom view of the design shown in FIG. 1.

The back of the front door lining forms no part of the claimed design. Additionally, the broken lines are for the purpose of illustrating portions of the front door lining and form no part of the claimed design.
